(57) **CLAIM**

The ornamental design for an auger, as shown and described.

DESCRIPTION

FIG. 1 is a perspective view of an auger showing my new design;

FIG. 2 is a side view thereof, the opposite side being a mirror image thereof;

FIG. 3 is another side view thereof similar to FIG. 2, but rotated 90° therefrom, the opposite side being a mirror image thereof;

FIG. 4 is a bottom view thereof; and,

FIG. 5 is a top view thereof.

1 Claim, 4 Drawing Sheets
